UNITED STATES PATENT OFFICE.

EDWARD F. RATE, OF CHICAGO, ILLINOIS.

GLOVE AND OTHER FASTENER.

SPECIFICATION forming part of Letters Patent No. 275,854, dated April 17, 1883.

Application filed August 21, 1882. (No model.)

To all whom it may concern:

Be it known that I, EDWARD F. RATE, residing at Chicago, in the county of Cook and State of Illinois, and a citizen of the United States, have invented a new and useful Improvement in Glove and other Fasteners, of which the following is a full description, reference being had to the accompanying drawings, in which—

10 Figure 1 is an elevation of the palm or front of a glove with the fastener applied to the wrist and in position when the wrist is open; Fig. 2, a detail, being an elevation of the wrist portion of the glove with the fastener applied thereto and in position when the wrist is drawn together or closed; Fig. 3, a top or plan view of the fastener detached; Fig. 4, an edge view of the fastener; Fig. 5, a top or plan view showing a modification of the fastener; Fig. 6, 15 a top or plan view showing another modification of the fastener.

The object of this invention is to construct a fastener which can be readily and easily applied to the wrist of a glove, and which will 20 do the required work of closing or drawing the wrist together in an effectual and reliable manner and without any trouble or inconvenience to the person wearing the glove; and it is designed primarily for use with coarse, 25 heavy, or working gloves or mittens, but can be used for other articles; and its nature consists in providing a slotted plate pivotally attached at one side or edge to one side of the wrist at the opening, and having its slot engaging with a stud attached to the wrist on the opposite side of the wrist-opening, all as hereinafter more specifically described, and 30 pointed out in the claims.

In the drawings, A represents the fastener, 35 which may be made by stamping, cutting, or otherwise forming from sheet-brass or other sheet metal or material. Three ways or forms of cutting or making this fastener A are shown in the drawings. In Fig. 3 the fastener is 40 formed with a straight or main portion, a, and extension or secondary portion a', and a lip or heel, a'', and is provided with a slot having a straight portion, b, and inclined portion b', with an enlargement or recess, b'', at its terminal end, and the lip or heel a'' is provided with a hole, c'. In Fig. 5 the fastener is made dou-

ble—that is, formed of two main or body portions, a, with extensions or secondary portions a' and two slots, b b', the inclined or secondary portions being joined, and in this form of 55 construction one of the extensions or secondary portions a' forms a lip or heel, a'', and, as shown, the inclined portion b' of the slots is not provided with the enlargement b''. In Fig. 6 the fastener is formed single, having a 60 main or body portion, a, and a lip or heel, a'', in which is an opening, c', with a slot, b, in the main or body portion, having at one terminal end an enlargement, b'', and at the other a hole or opening, b³. 65

B indicates a glove of any of the usual makes, having a wrist, B', with a slot or opening, C, for the passage of the hand. The form of fastener shown in Fig. 3 is applied to the glove by passing a rivet or stud, c, through the opening c' of the lip or heel a'' and through the wrist B' on one side of the wrist-opening C, and then capping or otherwise fastening, as shown in Fig. 1, so as to leave the fastener free to turn on the pin or stud as a pivot. The 70 pin or stud d is passed through the wrist B' on the opposite side of the opening C and through the slot in the fastening, and capped or otherwise fastened, as shown in Fig. 1, so that the two sides of the wrists will be connected through the pins or studs c d and the fastening A. The form of fastener shown in Fig. 5 is applied to the glove by passing the studs c d through the wrist B' on each side of the opening C, one of the pins passing through 75 the slot in one half of the fastening A and the other through the slot in the other half, attaching the fastener to the wrist, substantially the same as shown in Fig. 1, except that with the form shown in Fig. 5 the fastener 80 draws from both sides, the pins c d passing from one end of the slots to the other. The form shown in Fig. 6 is applied to the glove by passing a pin or stud through the hole c' of the lip or heel a'', the same as for the fastener of Fig. 3. The stud or pin d is secured to the glove-wrist B' on the opposite side of the opening C, and the fastener is connected therewith by passing the head of the stud or pin d through the opening b³, so that the stem 85 can enter the slot b. 90

In use the glove is slipped on the hand, as

usual, and the wearer, by drawing the opening C partly together with the other hand, can take hold of the end of the main body or portion *a* and turn the fastener into the position shown in Fig. 2, the stud or pin *d* with such movement passing to the terminal end of the portion *b'* of the slot, bringing the two pins or studs in line, or nearly so, so that they will work against each other and prevent the fastener from being easily turned back to unclasp or open the wrist; and for greater security in this regard the terminal end of the slot may have the enlargement *b''* to receive the stem of the stud or pin, and form a guard or lock by which the fastener will be held in its closed position.

This device is very simple in construction, can be readily applied, will not be liable to get out of order by being broken, and if broken or deranged in any manner can be readily replaced or repaired, and by giving it the peculiar form shown it will be seen that a strong leverage is produced for the size of the fastening, and at the same time the two studs or pins *c* and *d* are brought in line, or nearly so, and in such relation with the main portion of the fastening that the accidental unclasp of the glove cannot readily take place, as in order to unclasp the glove the wearer has to take hold of the free end and turn the fastening into the position shown in Fig. 1.

Although in the form shown in Fig. 6 the slot has no inclined or diagonal portion, the same result is produced, as the hole *c'* and the enlargement *b''* have the same relative relation to each other, as in the form shown in Fig. 3.

Although the fastener is shown applied to a glove, it is evident that it can be equally well applied to a mitten, and can also be applied to other articles for drawing two parts together.

What I claim as new, and desire to secure by Letters Patent, is—

The improved glove-fastening herein shown, 45 consisting of the lever-plate *A*, pivotally attached by a stud, *c*, on which it can turn on one side of the wrist-opening, and constructed with the curved slot, as described, and a pin fixed to the opposite side of the 50 wrist-opening and arranged to slide in the curved slot, whereby the turning of the lever-plate on its pivot will cause the curved slot and the fixed pin to coact and draw the edges of the wrist-opening together, substantially as 55 set forth.

EDWARD F. RATE.
